UNITED STATES PATENT OFFICE.

GEROLT GIBSON, OF ST. LOUIS, MISSOURI.

SASH-FASTENER.

SPECIFICATION forming part of Letters Patent No. 484,710, dated October 18, 1892.

Application filed March 10, 1892, Serial No. 424,392. (No model.)

To all whom it may concern:

Be it known that I, GEROLT GIBSON, a citizen of the United States, residing at St. Louis, Missouri, have invented certain new and useful Improvements in Sash-Locks; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to an improved lock for window-sashes, more especially for the upper sash, and it has for its objects, principally, to prevent lateral movement of the sashes in their grooves during the operation of locking the same; and it consists in the novel construction of devices, substantially as hereinafter more fully disclosed, and pointed out in the claims, whereby the aforesaid results may be obtained, together with the automatic locking of the upper sash in its closed position, which are illustrated in the accompanying drawings, in which—

Figure 1 is a view showing my invention as applied for use to a window, parts being broken away. Figs. 2, 3, and 4 are views showing the several members or parts of my invention in detail. Fig. 5 is a modification thereof.

In the embodiment of my invention I employ three parts or members A, B, and C, member A being suitably secured to the window-casing, the member B to the face of the upper sash, and the member C to the top of the lower sash.

The part or member A, besides its bracket or foot *a*, affording means for its attachment by screws or other suitable fastenings to the window is composed of a bifurcated arm *b*, integral with and offset from said bracket, providing a slot *c* between them. The side pieces of the bifurcated arm *b* are extended or carried outward and downward into the form of duplicate hooks *b'*, a space *b*² thus being provided between the edges of said duplicate hooks and the opposite edges of the side pieces of said arm, the whole constitut-

ing, substantially, a single hooked arm, the duplicating of said parts being to provide, as one, among other ways, for the pivoting of the latch, presently described, therebetween. The inner edges of the hooks *b'* are beveled outward and downward at their lower ends to readily guide the stud of the member B, as seen farther on, into engagement therewith and to secure a snug fit or wedging action thereat.

Between the upper ends of the side pieces of the arm *b* is pivoted or hung at its upper end a latch *c'*, having at its lower end a projection *c*², beveled or, rather, more nearly concave upon its upper edge, so as to slope outward and downward and yet slightly curve upward at its salient edge or point to effectually lift the upper sash into its closed position as said latch engages the member B, as more fully described hereinafter. The lower edge of the projection *c*² is rounded, having a general upward and outward inclination. At its extreme lowest end the latch *c'* has a stop or projection *c*³, adapted to engage a shoulder *c*⁴ upon the outer bottom edge of the space between the side pieces of the arm *b*, within which said latch swings to arrest or limit the outward movement of the latch.

The arm or casting *b* has projecting from its bottom or lower end a beveled catch *d*, and directly opposite the inner beveled side of said catch said end of the arm is provided with a plain-sided stop *d'*, slightly spaced off therefrom, thus providing a socket *d*² therebetween, said catch and stop being set inward from said end of the arm, leaving a shoulder *d*³ thereat.

The member B has at its upper end a forwardly-projecting stud *e*, having a beveled upper edge, as at *e'*, to expedite its passage past the projection *c*² of the latch *c'*, and a beveled lower edge to engage the beveled, somewhat slightly-concave edge of the projection *c*² of the latch *c'*, and at its inner lower end said member has a concave and a plain-sided stud *e*³; adapted to enter the socket *d*² of the member A, the concavity of the stud engaging the convexity of the catch *d*, while the plain-sided surface thereof engages the ad-

jacent side of the stop d' . The concave and plain-sided stud e^3 is arranged at the inner bottom edge of the body portion of the member B and faces in a direction at right angles 5 to that in which the stud e faces, said stud e^3 also having connection at its closed outer side with the inner edge of said body portion of the member B by a thickened portion or end piece e^2 , adapted to engage the shoulder d^3 of 10 the arm b , strengthening the same at that point.

The arm of the member B, bearing the stud e , is slightly curved or concave upon its outer edge, thus providing a shoulder e'' , upon 15 which the correspondingly-shaped lower end of one of the hooks b' rests or bears to combine with said hook in preventing edgewise movement of the sashes toward either side of the window frame or casing as the upper sash is 20 being shoved or pushed to the top, as in closing it.

The member C is also in the form of a hook, having its upper horizontal portion provided with a tooth f , said horizontal portion being 25 received into the slot c of the member A, and said tooth entering the space between the side pieces of the bifurcated arm b just in the rear of the latch c' , to lock the latter into engagement with the stud e of the member B. 30 The tooth f has a beveled surface f' upon its rear edge to engage a correspondingly-beveled surface f^2 of the inner bottom edge of the slot c , to cause the compact wedging together of the members A and C in effecting the locking 35 of the same together, while the shank of the member C has a plain offset f^3 directly opposite the beveled surface f' of the tooth f , to provide a square or solid surface of contact between it and said member during the wedging 40 action of the tooth on said member.

Assuming that the upper sash is open and it is desired to close and lock the same, the stud e of the member B, it will be seen, as the upper sash is shoved or pushed upward will pass or escape by the inwardly-yielding latch c' , and after such passage of the stud the latch will return by the action of gravity to its former 45 position, permitting its projection c^2 to pass under said stud, the hook b' guarding or guiding the stud in a direct vertical line, thus preventing the moving of the sashes edgewise, as would otherwise be the tendency in shoving the sashes home or into their closed position. The horizontal arm of the member C will then 50 enter the slot c of the member A, and, through its tooth engaging the latch, force the latch into such position as to cause the projection c^2 to engage at its upper edge the bottom edge of the stud e , the action of which, it is obvious, will 55 cause the stud e to ride upward thereon, and thus secure the automatic and effectual closing of the upper sash and firmly hold it against being jarred down to any extent. The coming together or engagement of the con- 60 cave stud e^3 and catch d and the wedging 65

action of the hook C upon the member A, bringing the meeting-rails of the sashes close together, have the effect to prevent the rattling of the sashes from the action of the wind or other cause.

In Fig. 5 is shown a modification of the parts or members A and B, it being understood, of course, that the part C is to be used in connection therewith in practice.

It will be understood that I make no claim 75 in this application to subject-matter claimed in my application filed July 27, 1891, and serially numbered 400,801, to wit:

"The combination of a member fixed to the casing, having a latch hung in an offset-arm 80 thereof, and a slot in rear of said arm, and said latch standing partially outward beyond said arm and partially in said slot, a member fixed to the upper sash, having a slot to engage said latch, and a member fixed to the 85 lower sash, having a hook to enter said slot and interlock the latch of the member fixed to the casing with the stud of the member secured to the upper sash."

Nor do I make claim in this application to 90 subject-matter claimed in my application filed February 23, 1892, and serially numbered 422,447, to wit:

"1. The combination of a member provided with a latch and in rear of said latch with a 95 slot having an inner beveled bottom edge, a second member having a beveled stud, and a third member having its hook portion provided with a tooth having a beveled surface, said member also having opposite the beveled surface of said hook a plain offset portion.

"2. The combination of a member provided with a latch, a beveled catch and a stop, spaced off from said catch, a second member having 105 a beveled stud and concave stud to engage said beveled catch and received between it and said stop, and means to effect engagement between the latch and said beveled stud."

Having thus described my invention, what I claim, and desire to secure by Letters Patent, is—

1. The combination of a member fixed to the casing, having an offset-arm provided with a 115 hook and a slot in rear of said arm and said arm having a latch whose forward end is adapted to stand at the entrance to the space between said arm and hook, a member fixed to the upper sash and having a stud to engage that portion of said latch at the entrance of said space, and a member fixed to the lower sash to enter the slot of the member fixed to the casing and to engage said latch with the stud of the member fixed to the upper sash, 120 substantially as set forth.

2. A sash-lock having one member provided with a latch and a hook having its lower free end beveled upon the inner edge outward and downward, a second member having a 130

stud beveled upon its upper and lower edges, and a third member having a horizontal portion adapted to enter a slot in the first-named part and engage said latch, causing the latch to act upon said stud and move it upward with the upper sash, substantially as set forth.

In testimony whereof I affix my signature in presence of two witnesses.

GEROLT GIBSON.
